ALARM LOCKSET

Felix Gilbert, New York, N.Y., assignor to General
Alarm Corporation, New York, N.Y., a corporation of Delaware

Filed Oct. 24, 1966, Ser. No. 4,402

Term of patent 14 years

(Cl. D50—5)

FIG. 1 is a front elevational view of an alarm lockset embodying my new design;
FIG. 2 is a left side elevational view;
FIG. 3 is a right side elevational view;
FIG. 4 is a top plan view of said lockset; and
FIG. 5 is a partial cross-sectional view taken along line 5—5 and shown broken away for convenience of illustration.

I claim:

The ornamental design for an alarm lockset, as shown and described.
